UNITED STATES PATENT OFFICE.

SARAH W. TRABUE, OF GIRARD, ILLINOIS.

BALING-PRESS.

SPECIFICATION forming part of Letters Patent No. 376,688, dated January 17, 1888.

Application filed July 15, 1887. Serial No. 244,395. (No model.)

To all whom it may concern:

Be it known that I, SARAH W. TRABUE, a citizen of the United States, residing at Girard, in the county of Macoupin, and State of Illinois, have invented a new and useful Improvement in Baling-Presses, of which the following is a specification.

My invention relates to an improvement in baling-presses; and it consists in the peculiar construction and combination of devices, that will be more fully set forth hereinafter, and particularly pointed out in the claims.

In the accompanying drawings, Figure 1 is a side elevation of a baling-press embodying my improvements. Fig. 2 is a vertical longitudinal central sectional view of the same. Fig. 3 is partly a top plan view and partly a horizontal sectional view. Fig. 4 is a vertical transverse sectional view taken on the line $\alpha\alpha$ of Fig. 1. Fig. 5 is a detached perspective view of the feeder. Fig. 6 is a front view of the press. Fig. 7 is a detached perspective view of the pitman connecting the follower to the crank-shaft. Fig. 8 is a detached elevation, partly in section, of one of the removable partition-boards.

A represents a pair of ground-sills, which are arranged parallel with each other, and are connected by means of a series of transverse beams, B.

C represents a floor or platform, which is arranged between the sills A and extends for a suitable distance thereon, the said floor or platform being supported by the beams B. At a suitable distance from the rear ends of the ground-sills the floor or platform is provided with a series of vertical longitudinal openings, D.

E represents a pair of longitudinal beams, which are of the same dimensions as the ground-sills, and are arranged above the latter, and are supported by vertical standards F, F', F'', and F''. The standards F' and F'' project above the sills E a considerable distance, as shown.

G represents side walls, which are secured to the inner sides of the standards F and F' and extend from the beams E to the sills A. The beams E are connected together by means of the cross-beam H at their rear ends, a cross-beam, I, arranged transversely between the standards F', and a beam, K, at the front ends of beams E on the upper sides thereof.

H' represents a pair of cross-beams, which also connect the beams E, and are arranged at suitable regular distances between the beams H and I.

L represents a platform, which is arranged between the beams E and extends forward thereon from the cross-beams H' to a point in line with the standards F, the said platform forming the upper side of the press-box, of which the floor or platform C forms the lower side. On the upper sides of the beams E, and extending rearward from the standards F' a suitable distance, are side walls L', which are provided in their outer sides with longitudinal horizontal grooves M.

N represents horizontal longitudinal open slots, which are made in the walls L', extend forward from the rear sides thereof to a point in line with the front sides of standards F, and there communicate with vertical downward-extending slots O. The said slots N and O communicate with the grooves M.

P represents a platform, which constitutes the bottom of the feed-hopper, and is secured on the upper sides of the beams H' and connects the same. The sides of the feed-hopper are formed by the side walls L'', and the front thereof is formed by a transverse wall, R, which is arranged in line with the rear sides of standards F'.

S represents a hay-condenser, which comprises the front and rear sides, T and U, respectively, the guide-bars V, which are attached to the ends of the rear side, U, and extend forward and fit in the grooves M, and the top or cover W. Pivotal bolt-rods X extend through the front ends of the guide-bars V, pass through the slots N, and enter the ends of the front side, T.

Inasmuch as the platform P terminates at the front cross-beam, H', the front portion of the feed-hopper is bottomless.

Y represents a transverse holder, which is arranged on the front end of the platform P, and is provided at its upper corners with projecting arms Z, that extend through the slots O and enter the grooves M. Spring-arms A' have their rear ends attached to the upper sides of the beams E and their upper front ends attached to the ends of arms Z, the said springs being arranged in the grooves M in the paths of the guides V of the hay-compressor,

and are adapted to normally raise the holder, as shown in dotted lines in Fig. 1. On the front side of the holder Y is a cross-board, B', which connects the side walls of the feed-hopper.

The rear end of the platform or top L of the press-box is not secured either to the beams E or to the cross-beam H, and is thereby adapted to be depressed.

D' represents a screw which engages a vertical opening in the center of the beam H and bears upon a plate on the upper side of the top or platform L, at the rear end thereof, the function of this screw being to force the rear end of the platform downward in the position shown in Fig. 2, and thereby cause the said platform to be inclined downward rearwardly toward the bottom platform, C, for the purpose to be hereinafter explained.

E' represents a pair of vertical bolt-rods, which connect the rear ends of the sills A and the beams E and prevent the latter from springing upward from the sills. The grooves M in the sides L' of the feed-hopper are covered by means of detachable metallic plates F¹², thereby preventing hay or other foreign substance from entering the grooves M and interfering with the operation of the machine. The side walls G of the compression-chamber 30 of the press-box are provided with horizontal slots G' near their upper and lower sides.

I' represents vertical rods, which extend from the sills A to the beams E on the other sides of the sides G and at suitable distance in rear of the standards F', and on the said rods are pivoted detents K', which work in the slots G', extend longitudinally through the same, and are provided at their frontends with arms L'. The arms L' are connected in pairs by 40 vertical bars M'.

N' represents coiled extensible springs, which bear between the sides G and the opposing inner sides of the bars M', and serve normally to turn the detents K' on their pivotal rods, so that the rear ends of the detents are caused to project beyond the inner sides of the sides G. Stop-pins O' are provided for the detents K', to limit the movement of the latter.

P' represents a follower, which is adapted 50 to move longitudinally in the press-box and to slide upon the bottom platform, C. The said follower is provided at its front corners with vertical arms R', which project above its upper side.

S' represents a leaf, which has its front end pivoted between the upper ends of arms R', the said leaf extending rearward over the follower and being arranged at a suitable distance above the same. A spring, T', has its 60 front end secured on the upper side of the follower. The rear end of the said spring bears under the leaf S' to normally raise the same. The upper side of the leaf S' is covered by a metallic plate, U', and the rear end of the said plate is bent downward over the rear end of the leaf and extends to the rear side of the follower to form a depending shield, V', to

close the space between the opposing sides of the leaf and the follower. In the sides of the follower are diagonal grooves W', which coincide with the slots G'. The said grooves are deeper at their rear ends than at their front ends, and are thereby adapted to force the rear ends of the detents K' outward as the follower moves in the press-box, thereby moving the 75 detents out of the path of the follower.

X' represents a transverse driving-shaft, which is journaled in a pair of blocks, Y', on the upper sides of beams E, near the front ends thereof. To the center of this shaft is attached 80 a driving-pulley, Z'.

A² represents a pair of fly-wheels, which are attached to the shaft X' on opposite sides of the pulley Z'. On the outer ends of the shaft X', which project beyond the outer sides of the 85 blocks Y', are feathered spur-pinions B². Coiled extensible springs C² are placed on and are secured to the outer ends of the shaft X' and bear against the outer sides of the pinions.

D² represents a transverse shaft which is 90 journaled in bearing-blocks E² on the beams E at a suitable distance in front of shaft X'. The said shaft D² is provided with spur-wheels G², which mesh with the pinions B². On the ends of the shaft D², which project beyond the 95 wheels G², are secured pinions H².

I² represents a shaft which is journaled in bearing-blocks on the rear sides of standards F². The ends of this shaft are provided with spur-wheels K², which mesh with pinions D², and at 100 the center of the shaft is a crank, L².

M² represents a pitman, which has its front end connected to the shaft and its rear end pivoted to a head, N², that projects from the front side of the follower P'. A block, O², is 105 rigidly secured to this head and projects forward therefrom, and in the upper end of the said block is a transverse horizontal groove, P².

R² represents a transverse beam which connects the upper ends of the standards F², near 110 their upper ends. In the upper ends of the said standards is journaled a shaft, S², which forms the fulcrum for a walking-beam, T². The outer end of the said walking-beam is connected to crank-pins U', with which the wheels K² are provided, by means of connecting-rods 115 V². To the rear end of the walking-beam is pivoted the upper end of a vertically-movable feeder, W². Rods X² are pivoted to the said feeder and to eyebolts on the rear side of cross-bar R², the said rods serving to keep the feeder 120 in substantially a vertical position. The lower end of the feeder has a vertically-adjustable extension, Y².

It will be observed by reference to Figs. 1 125 and 2 that the feeder is arranged over the bottomless portion of the feed-hopper, and is adapted to move downward through the same and to enter the compression-chamber of the press-box when the wheels K² are rotated and the walking-beam is caused to oscillate. The extension G² is extended at full length below the feeder when the press begins to operate, and is thereby adapted to reach the bottom of 130

the compression-chamber on the downstroke of the feeder. As the successive stratas of material gradually fill the compressing-chamber, the extension G² of the feeder is moved upward 5 on the same by the material in the compression-chamber as the feeder moves downward, thereby preventing too great strain from being exerted on the feeder.

Z² represents a horizontal shaft, which is 10 journaled in a transverse opening made in the center of cross-bar R². To the front end of this shaft is attached a wheel, A³, and to the rear end thereof is attached the lever-arm B³.

C³ represents a pair of guiding-sheaves, 15 which are attached to the ends of beams R² and extend rearward therefrom. D³ represents similar sheaves, which are journaled in the upper ends of standards F'. Operating-cords E³ are attached to the lever-arm B³ and 20 pass over the sheaves C³ and D³.

To the front sides of the standards F', near the upper ends thereof, are fulcrumed levers F³, the lower ends of which are arranged on the inner sides of the pinions B². The upper 25 ends of these levers are connected to the crank-wheel A³ by means of rods G³.

H³ represents a yoke, which has the rear ends of its arms attached to the bolts X, that project beyond the outer sides of the guide-arms V of the hay-compressor. The arms of 30 the said yoke extend forward from the grooves M in the sides of the feed hopper, and the front transverse portion of the yoke is secured in the slot P² in the upper end of block O².

I³ represents a pair of vertical standards, 35 which extend from the beams E, near the rear ends thereof, and in the upper ends of the said standards are vertical longitudinal open slots K³.

L³ represents a gong, which is attached to the outer side of one of the beams E. A rock-shaft, M³, is journaled vertically in the said beam, has its upper end bent outward and provided with a hammer, N³, adapted to strike 45 the gong and sound the same, and the lower end of the said rock-shaft is bent at right angles to form an operating-arm, O³.

P³ represents a coiled retractile spring, which is connected to the arm O³ and serves to move 50 the latter forward, and thereby keep the hammer normally bearing against the gong.

R³ represents a series of follower or bale partitions, which are adapted to be inserted in the front side of the compression-chamber 55 of the press-box by lowering them in the bottomless front portion of the feed-hopper, so as to arrange the partitions in rear of the follower. Each of the said partitions is provided in one side with a pivoted spring-actuated 60 tappet-arm, S³, the upper ends of which are normally projected beyond the edges of the partitions, and are arranged under the beam E, to which the gong is attached. Each beam E is provided on its outer side with a pair of 65 keepers, T³.

U³ represents a foot-board or platform, which is provided at its inner edge with a pair of

hooks, V³, adapted to engage either pair of keepers T³. Plates W³ are hinged on the upper side of the foot-board or platform, near the 70 inner edge thereof, and these plates are adapted to fold down upon the said platform and to project beyond the inner side thereof to the opposing plate, F¹², of the feed-hopper, and thereby bridge the space between the inner 75 edge of the foot-board or platform and the side of the feed-hopper.

X³ represents a pair of supporting-legs, which are hinged under the outer corners of the foot-board or platform, and are thereby adapted to 80 fold under the same. The said supporting-legs are connected together by a cross-board, Y³, and are further provided with hooks Z³, adapted to engage eyes or staples A⁴ on the sides of the foot-board or platform, so as to secure the supporting-legs in a vertical position, and thereby raise the outer edge of the platform 85 a suitable distance above the ground. Studs B⁴ project beyond the outer sides of the foot-board or platform, and a rod, C⁴, extends 90 through the aligned openings in the said studs, and is arranged beyond the outer side of the platform or foot-board.

D⁴ represents a perforated screen, which is provided on its under side near its center, near 95 one edge, with a pair of depending bracket-arms, E⁴, which are journaled on the rod C⁴, and are adapted to slide longitudinally thereon. This screen is thereby adapted to turn toward the feed-hopper and rest against one side of 100 the same in an inclined position. By hinging the said screen to the foot-board or platform and enabling it to be adjusted longitudinally thereon the screen may be moved to one end of the platform, no matter to which side of the 105 press box the latter may be attached, and thus provide room on the platform for the person who feeds the hopper to stand upon.

F⁴ represents an awning board, which is provided at its inner corners with projecting trunnions G⁴, which are adapted to fit in the slots K³ of standards I³ and in horizontal openings or recesses H⁴ on the rear sides of standards F'. The said awning board is provided at one end with a hook, I⁴, adapted to engage keepers K⁴, with which the rear sides of standards F' are provided. The awning board is attached to the side of the feed-hopper opposite the foot-board or platform, and this inclined board or screen is adapted to prevent loose hay, dust, 115 and seeds from falling upon the person whose duty it is to tie the bales as they are formed.

The operation of my invention is as follows: When the driving-shaft is set in motion, the walking-beam is caused to oscillate, so as to 120 work the feeder W² vertically in the press-box and to move the follower longitudinally back and forth therein. At the initial rearward movement of the follower the latter forces one of the partitions R², which has been 125 previously placed against its rear side, rearward through the compression chamber of the press-box until the detents K' engage the front side of the said partition and prevent the same 130

from following the follower as the latter reverses its movement and moves forward in the press-box. The operator, standing on the platform or foot-board U^3 , throws a quantity of hay 5 into the feed-hopper, and as the follower moves forward in the press-box the hay-condenser, which is connected to the follower by means of the yoke, moves forward in the hopper, and thereby packs the hay into the front bottom-10 less portion of the hopper. On the succeeding rearward motion of the follower the hay-condenser moves rearward, thereby releasing its compression of the hay in the hopper, and the feeder W^2 descends upon the said hay and forces 15 it downward into the compression-chamber of the feed-box, where it is forced by the rearward movement of the follower against the partition-board R^3 . The latter yields to the pressure of the hay and moves rearward in the press-box. 20 On the succeeding forward stroke of the follower the holder Y is forced downward by reason of the guide-arms V of the hay-condenser moving forward over the forward upwardly-inclined spring-arms, A' , thereby causing 25 the holder to engage the hay that is compressed against the partition and preventing the same from moving forward after the follower. At each succeeding rearward stroke of the follower an additional quantity of hay 30 is packed against the partition, and the latter moves farther and farther rearward in the press-box until a sufficient quantity of hay has been pressed to form a bale, when the operator, stationed on the platform or foot-board U^3 , inserts another partition in place, and the operation 35 before described is repeated. The gong, hereinbefore described, is arranged at a distance in rear of the compression-chamber of the press-box equal to the desired length of the 40 bales, and thereby, as each partition-board in succession moves rearward past the gong, its spring-actuated tappet arm S^3 engages the arm O^3 of the gong-hammer and operates the same, thereby causing the gong to sound, which is 45 the signal for the operator to insert another partition in the front end of the compression-chamber. The screw D' is turned down, so as to depress the rear end of the platform L , and thereby offer so much resistance to the rearward motion of the hay as it is driven back by 50 the follower as to cause the hay to be compactly compressed. As the hay moves rearward in the press-box, the attendants pass wires or cords around the bales and fasten them. After 55 the press-box becomes completely filled with bales of hay, each additional bale that is formed causes the bale at the rear end of the press box to be ejected therefrom, as will be very readily understood, and the partition-boards ejected 60 with the bales are picked up and used again in the press, as before.

If it be desired to stop the operation of the press at any time, this may be accomplished by grasping one of the cords E^3 and drawing 65 down upon the same, thereby causing the cord to operate the lever-arm B^3 and turn the shaft Z^2 and cause the crank-wheels A^3 to operate

the levers F^3 , so as to move the pinions B^2 outward on the ends of the driving-shaft and release them from engagement with the wheels G^2 . 70

Between the extreme front ends of the beams E is journaled a roller, K^3 , which supports the lower side of the endless belt that passes over the driving-pulley and prevents the crank L^2 from coming in contact with the said bolt. 75

Having thus described my invention, I claim—

1. The combination of the press-box, the follower therein, the feeder-hopper on the upper side of the press-box having the horizontal grooves M in the sides, and the slots N , communicating with the said grooves, the condenser movable longitudinally in the feed-hopper and having the front T in said hopper, the guide-arms V , working in the grooves M , 80 and the pins or bolts X , connecting the said guide-arms and the front T and extending through the slots N , substantially as described. 85

2. The combination, in a baling-press, of the press-box, the follower, the vertically-movable holder Y , the spring to normally elevate the same, and the hay-compressor movable in unison with the follower and adapted to automatically depress the holder when the hay-compressor advances, substantially as described. 90

3. The combination, in a baling-press, of the press-box, the holder Y , having the spring-arms A' , to normally elevate the same, and the hay-compressor movable in unison with the follower and provided with the arms V to bear upon the springs A' , substantially as described. 100

4. The combination, in a baling-press, of the feed-hopper on the press-box, having the horizontal grooves M in its sides, the hay-condenser movable in the feed-hopper and having the guide-arms V , working in grooves M , and movable plates F^{12} , secured to the sides of the feed-hopper and covering the grooves M 110 and the arms V , substantially as described.

5. The combination of the press-box, the feed-hopper thereon having the grooves M in its sides, the holder Y , having the spring-arms to normally elevate the same, said spring-arms being located in the lower sides of the grooves M , the compressor movable longitudinally in the feed-hopper and having the guide-arms V , working in the grooves M and adapted to depress the spring-arms, and the removable plates F^{12} , secured to the sides of the feed-hopper and covering the grooves M and the mechanism therein, substantially as described. 115

6. The combination of the press box having the compression-chamber, the feed-hopper arranged over the press-box and extending over the compression-chamber, the vertically-movable holder Y , arranged at the rear upper side of the compression-chamber and having the spring-arms A' , to normally raise the same, the follower arranged in the press-box, the hay-condenser arranged in the feed-hopper and adapted to slide therein, the said hay-condenser having the arms bearing on the spring- 120

125

130

arms A' to operate the holder, and the yoke connecting the condenser to the follower, substantially as described.

7. The combination, in a bale-press, of the press-box having the feed-hopper on its upper side and the platform or foot-board U³, adapted to be attached to the press-box and having the screen E⁴ connected thereto and movable longitudinally thereon, the said screen being adapted to bear against the feed-hopper, substantially as described.

8. The combination, in a baling-press, of the press-box having the keepers T³ on its sides and the foot-board or platform U³, having the hooks at one edge to engage the keepers and provided with the hinged plate W³ and the supporting-legs, for the purpose set forth, substantially as described.

9. The combination of the foot-board, the platform U³, adapted to be attached to the press-box of the baling-press and having the guide-rods C⁴ at its outer side, and the screen hinged to the said guide-rod and movable longitudinally therein, substantially as described.

25 10. The combination, in a baling-press, of

the press-box having the feed-hopper on its upper side, the follower movable in the press-box, the hay-condenser movable in the feed-hopper and connected to the follower and actuated thereby, the walking-beam, the 30 feeder pivoted thereto and extending downward into the hopper and adapted to descend in the press-box, the crank-shaft, the pitman connecting the same to the follower, the rods connecting the crank-shaft to the outer end of 35 the walking-beam, the driving-shaft geared to the crank-shaft and having the feathered pinions, and the levers to throw the said pinions out of engagement with the gears, substantially as described.

40 11. The feeder W², having the adjustable extension Y², for the purpose set forth, substantially as described.

In testimony that I claim the foregoing as my own I have hereto affixed my signature in 45 presence of two witnesses.

SARAH W. TRABUE.
